UNITED STATES PATENT OFFICE.

WILLIAM H. BOERUM, OF YUKON, FLORIDA, ASSIGNOR OF ONE-HALF TO JAMES E. WARE, OF YUKON, FLORIDA.

SPARK ARRESTER.

Application filed June 25, 1918. Serial No. 241,787.

To all whom it may concern:

Be it known that I, WILLIAM H. BOERUM, a citizen of the United States, residing at Yukon, in the county of Duval and State of Florida, have invented certain new and useful improvements in Spark Arresters; and I do hereby declare the following to be a full, clear, and exact description of the invention, such as will enable others skilled in the art to which it appertains to make and use the same.

This invention relates to improvements in spark arresters, and has for one of its objects the provision of a device of this character to prevent the sparks from issuing from smoke stacks and chimney flues, and is especially adapted for arresting sparks from the tent flues, thereby obviating the danger of the sparks igniting a tent or inflammable roof. Another object of this invention is the provision of an insert for a smoke stack, chimney or tent flue, having a foraminous member to prevent the spark from passing beyond the same, and which is adapted to be located in close proximity to the fire so that the heat therefrom will burn the carbon, soot and creosote deposits from the material of the device, thus preventing clogging of the draft.

A further object of this invention is the provision of means whereby the foraminous member can be conveniently cleaned without removing the device from the smoke stack, including all the tent flues.

A still further object of this invention is the provision of a spark arrester of the above-stated character, which will be simple, durable and efficient, and which may be manufactured and sold at a comparatively low cost.

With these and other objects in view, as will become more apparent as the description proceeds, the invention consists in certain novel features of construction, combination and arrangement of parts as will be herein-after more fully described and claimed.

For a complete understanding of my invention, reference will be had to the following description and accompanying drawings, in which:

Figure 1 is a perspective view of a spark arrester constructed in accordance with my invention,

Figure 2 is a fragmentary vertical sec-

tional view of the inserts, illustrating the 55 arrester,

Figure 3 is a similar view, showing the arrester in an inoperative or cleaning position,

Figure 4 is a plan view of the arrester, 60

Figure 5 is a side elevation of a modified form of the invention,

Figure 6 is a transverse sectional view, taken on the line 6-6 of Figure 5,

Figure 7 is a vertical sectional view of my 65 modified form of invention, illustrating how a portion of the arrester may be cleaned while the remaining portion prevents the issuance of the sparks through the insert.

Referring in detail to the drawings, the 70 numeral 1 indicates an insert adapted to be positioned between the sections of a smoke stack, tent flue and the like, and consists of end portions 2 and 3, which are adapted to be inserted within the ends of the adjoining 75 sections of a smoke stack or tent flue. The end portions 2 and 3 are connected by a rectangular portion 4, provided with a slot to receive the spark arresting frame 5, and has secured to one end a hand grip 6 projecting 80 exteriorly of the rectangular portion 4, so that the frame may be readily removed and replaced into the insert 1. A plurality of overlapping spark-arresting shutters 7 are 85 pivotally mounted upon transversely extending rods 8 carried by the frame 5, and each consists of a frame 9 of substantially rectangular formation covered by foraminous material 10. The foraminous material 10 is preferably constructed of wire mesh, which 90 is capable of withstanding considerable heat. The normal position of the shutters 7 are substantially horizontal, as clearly illustrated in Figure 2, so as to arrest the sparks and prevent them passing through the insert 1.

Substantially L-shaped rods 11 have one of their ends bent to form hooks 12, which engage over the free ends of the shutters 7, while the free ends of the other arms are pivoted to an operating rod 13. Pins or pivot forming members 14 are carried by the frame 5, and engage the substantially L-shaped arms 11 at their curved portions, so that upon sliding movement of the operating rod 13 the shutters will be moved into either a vertical or horizontal position according to the movement of said rod. 105

The operating rod 13 extends exteriorly of the insert 1, and has formed thereon a handle 15, so that the operating rod can be readily reciprocated to swing the shutters 7 into vertical or horizontal position. By operating the rod 13 with considerable force, the shutters 7 will be caused to hit against the frame 5 and dislodge soot and other foreign matter that may accumulate thereon, thus rendering the device capable of being cleaned without removing the frame 5 from the insert 1. However, the frame may be removed if desired and the shutters 7 cleaned in any well known manner.

15 Referring to my modified form of invention, it consists of an insert 16, consisting of end members 17, which are adapted to be inserted within the sections of a smoke stack, or end flue, and are connected by an intermediate portion 18. The intermediate portion 18 is secured to the end members 17 by interlocking the ends of said members, as illustrated at 19, but, however, any other form of connection may be readily employed if desired. The intermediate portion 18 is provided with oppositely disposed slots to receive a frame 20, which carries foraminous material 21. The frame 20 projects beyond the intermediate portion 18, so that a portion of the foraminous material may be cleaned, while the remaining portion of the foraminous material on the frame acts as an arrester within the intermediate portion 18.
